UNITED STATES PATENT OFFICE

WILLIAM DEUTSCH, OF DETROIT, MICHIGAN

DEMOUNTABLE SHAVING BRUSH

Application filed April 23, 1931. Serial No. 532,269.

This invention relates to a special shaving brush, certain features of which were shown in my former patent application Serial No. 419,256, filed Jan. 8, 1930 which has matured into Patent No. 1,846,091.

The object of my invention is to produce a special shaving brush whereby the brush head may readily be drawn within a small handle casing, or ejected therefrom, and 10 without demounting the brush from said casing.

Another object is to produce a demountable shaving brush that can easily be carried in the pocket when not in use, and that will 15 have the appearance of a fountain pen.

A further object is to produce a combination brush and soap tube casing, that will serve as a brush handle when opened, and that may be readily joined to a similar razor 20 casing for forming a complete shaving set in one unit.

These several objects are attained in the preferred form by the construction and arrangement of parts more fully hereinafter 25 set forth.

Similar parts on the drawing are marked by similar numerals or letters.

Fig. 1 is a side view of my device showing the exterior casing arrangement.

30 Fig. 2 is an end view of the brush end showing the soap cream casing discharge end.

Fig. 3 is a longitudinal sectional view taken on the lines 3—3 of the Fig. 2 showing 35 the general arrangement of the interior operating parts.

Fig. 4 is a cross sectional view taken on the line 4—4 of the Fig. 3 showing the operating disc and shaft for the brush section.

40 Fig. 5 is also a cross sectional view taken on the line 5—5 of the Fig. 3 showing the brush head and connected operating screw shaft.

Fig. 6 is a side view of the casing with 45 the brush section withdrawn therein and the casing closed with an end cap.

Fig. 7 is also a side view of the casing as closed by attaching to a similarly constructed demountable razor section, instead 50 of using the end cap as shown in the Fig. 6.

While I have shown the views in the drawing in enlarged sections for the purpose of more clearly illustrating the mechanical details, it is intended that the finished product be much smaller, and of a size and 55 design to present the appearance of an ordinary fountain pen, and for carrying in the pocket in a similar manner.

I will now describe more fully the detailed construction of my device, referring 60 to the drawing and the marks thereon.

In general, my demountable shaving brush comprises a tubular casing closed at one end by an attached end cap, and having 65 a shaving brush head slidably mounted therein, said brush head being actuated with in the casing by means of a connected screw shaft rotatably mounted on the casing head.

The casing —1— may be made of thin 70 metal, or of any other suitable material such as hard rubber, bakelite, etc., and is formed of a tubular section —1—, open at both ends thereof, one end being provided with threads —a— for screwing a threaded end cap —2— 75 thereon. The opposite casing end is formed with a narrow external flange —b—, encircling the outer end wall, and carries rotatably mounted thereon a turning ring —3— also formed with an internal flanged 80 collar —c— designed to engage the casing flanged —b— and turn thereon. Within the turning ring —3— is fixedly mounted a disc plate —4— tightly pressed within the ring walls and positioned to engage the cas- 85 ing ends when the casing and ring flanges are together, thus securely but rotatably mounting the turning ring thereon. The open edge of the turning ring is provided with internal threads —c— for receiving 90

therein a correspondingly threaded soap cream cup —5—, and which may be easily detached therefrom by unscrewing the section. Mounted on the center of the ring disc —4— is a threaded operating screw —6—, 95 fixedly attached to the disc center and positioned concentric with the casing axis, said screw —6— being rotatable directly with the connected turning ring. Slidably mounted inside the opposite casing end is a cy- 100

- lindrical plug brush head —7—, capable of being moved the entire length of said casing, said brush head being formed with a central tubular recess —8— also coinciding 5 with the casing axis, and is designed to allow the operating screw —6— to be passed therethrough, said operating screw being connected to the brush head —7— by a small pin —9— fixedly mounted through the brush 10 head and projected within the central recess opening, engaging the operating screw threads —d—, causing an endwise movement of the head —7— within the casing —1— upon any rotation of the turning ring —3—. 15 The pin —9— is also extended beyond the outer wall of the brush head for engaging the wall slot —e— formed lengthwise of the inside casing wall, and serves to prevent rotation of the brush head as the operating 20 screw is turned. Suitable brush bristles —10— are mounted within the brush head in the ordinary manner for mounting bristles of this character, the quality of bristles being varied as desired. Small holes —f— are 25 preferably formed through the ring disc —4— to provide ventilation therethrough for more easily drying the brush after using. Within the soap cream cup —5— is slidably mounted a discharge disc —11—, formed with a rigid guide pin —12— positioned at right angles thereto and along the casing axis, said guide pin being projected through the casing end hole —g—, and prevents the disc from any side displacement 30 therein. Through the outer end of the soap cream cup —5— are formed a series of soap cream passages —h—, and through which the soft cream soap —k— as placed within the cup, may be forced by depressing the discharge disc —11— with the thumb, when said cup is detached from the supporting ring —3—, thus providing soap 35 cream for use with the shaving brush —10— as desired. The cup —5— may be readily refilled by removing the discharge disc —11— therefrom, filling the cup with soap cream in the ordinary manner, then replacing the discharge disc therein. 40 When the demountable shaving brush is not in use it may be withdrawn within the casing —1— by rotating the turning ring —3—, and the end cap —2— attached as indicated in the Fig. 6 of the drawing. 45 If desired, my demountable brush may be closed by attaching same to the casing end of my demountable razor section more specifically described in my former patent application Serial No. 419,256, and for which the 50 brush is especially designed and intended, as indicated in Fig. 7, the combined sections resembling a fountain pen, and is intended to be carried in the pocket in a similar manner. 55 Having fully described my demountable

shaving brush, what I claim as my invention and desire to secure by Letters Patent is:

1. A demountable shaving brush adapted for carrying in the pocket, comprising a tubular casing suitable for a handle member and threaded at one end, said casing being formed with a narrow wall slot lengthwise of the inside wall thereof, a shaving brush head with bristles attached slidably mounted within the threaded casing end, 70 pin means mounted on the side of said brush head for engaging said casing wall slot and sliding therein, a turning ring rotatably mounted on the opposite casing end, an operating screw fixedly attached to said turning ring and positioned centrally lengthwise said casing axis, said operating screw being threadably connected through the brush head and capable of passing therethrough for sliding same lengthwise of said 75 casing as the turning ring is rotated.

2. A demountable shaving brush adapted for carrying in the pocket, comprising a tubular casing suitable for a handle member, threaded at one end and formed with an 80 external flange collar at the opposite end thereof, said casing also being provided with a longitudinal internal wall slot, a shaving brush head with bristles attached slidably mounted within the threaded casing end, 85 pin means mounted in the side of the brush head for engaging the casing wall slot and sliding therein, a flanged turning ring threaded at the open side, rotatably mounted on the opposite casing end, said flanged 90 ring engaging the casing end flange and rotatable thereon, a lock disc fixedly mounted within said turning ring and positioned to engage the casing end, an operating screw 95 fixedly mounted within the center of said lock disc and extended lengthwise of said casing, said operating screw being rotatable with the turning ring and threadably connected through the shaving brush head passing therethrough for sliding same lengthwise of the tubular casing as the turning ring 100 is rotated.

In witness whereof I sign these specifications.
